UNITED STATES PATENT OFFICE

RICHARD J. COACH, OF CLEVELAND, OHIO, ASSIGNOR TO THE SUB-SURFACE VACUUM DEVELOPMENT COMPANY, OF CLEVELAND, OHIO, A CORPORATION OF OHIO.

EVAPORATOR.

1,220,194.

Specification of Letters Patent. Patented Mar. 27, 1917.

Application filed April 1, 1912. Serial No. 687,321.

To all whom it may concern:

Be it known that I, RICHARD J. COACH, a citizen of the United States, residing at Cleveland, in the county of Cuyahoga and 5 State of Ohio, have invented a certain new and useful Improvement in Evaporators, of which the following is a full, clear, and exact description.

The object of this invention is to produce 10 a rapid evaporation of fluids with a minimum expenditure of heat units.

The invention consists primarily in an evaporating pan for containing the fluid, a heating coil, and means whereby said coil 15 is made to travel repeatedly in a path which carries it down into, and then along in, and then out of said fluid. It also consists in the combination with such means of a vacuum producing device to promote evapo- 20 ration and to carry away the produced vapor. It also consists of various other novel features of construction, and combinations of parts which are shown in the drawings and hereinafter described, all of 25 which will be definitely pointed out in the claims.

The drawing shows an apparatus which is organized with special reference to its use 30 for evaporating milk, but it may, of course, be used for evaporating other fluids and is susceptible of modification to adapt it for any special use.

In the drawing, Figure 1 is a sectional side elevation of a machine embodying the 35 invention. Fig. 2 is a vertical transverse section.

Referring to the parts by reference letters, 1 represents the evaporating chamber having a pan-shaped bottom. This chamber preferably has a steam jacket or space 2 beneath it into which steam may be delivered from perforated pipes 3, said space having a water outlet 4.

There are air passages 5 at the sides of 45 the evaporating chamber extending the entire length thereof; and in the walls of said chamber are longitudinally extended slots 6 through which vapor may be drawn from the chamber into said passages. These passages are connected with a suction fan 7 or other suitable vacuum producing instrumentality. In the specific construction shown the passages communicate at their lower 50 ends with a space 8 below the steam jacket; and the suction fan is connected with this

space. These air passages and space 8 surround the evaporating chamber on three sides. The vapor drawn through these passages and space is hot, and as it flows through the stated paths will give up some 60 of its heat to the walls of said chamber.

Above the evaporating chamber is a crank shaft 9 from the cranks of which two bars 10 are loosely hung. These bars may each be formed of two parts connected by a turn buckle 10^a, by which they may be strengthened or shortened as required. The end members 12 of the coil supporting frame 13 are loosely suspended from the lower ends of 70 these bars.

14 represents a steam coil which is supported by said frame. The inlet end of this coil 14^a is connected by a flexible pipe 16 with a steam supply pipe 19. The discharge end 14^b of said coil is connected by a flexible 75 pipe 17 with a water discharge pipe 18.

The term "coil" as used is not intended to imply that it must consist of any particular number of pipes or that they should be connected in series, or have any particular 80 form. The coil may, in fact, consist of one or more pipes, if means are provided for causing steam to pass through them. In the particular construction shown the coil consists of pipe bent fanwise to form a plurality of parallel transversely extended 85 tubular members which are connected in series and lie all in the same horizontal plane.

The bars 10 and the flexible tubes 16 and 90 17 pass out of the evaporation chamber through holes 10^a in the cover or top 20 of said chamber. In order that a suitable degree of suction in the evaporating chamber may be produced by the suction fan, these 95 holes are made as small as circumstances will permit.

In using this machine so much of the fluid to be evaporated is placed in the evaporating chamber 1 as will bring the surface level 100 thereof in such a plane that the coil will be lifted above the surface when raised, and will be submerged when lowered.

As the shaft 9 is rotated, the steam coil will be plunged down into the fluid and 105 caused to move transversely therein in a short curved path and to be then withdrawn, this movement being repeated with each revolution of the shaft. The shaft is preferably rotated at such a speed that as the coil 110

enters the fluid it will entrain or draw in with it some air. The heated coil will evenly impart some of its heat to the fluid with which it contacts, and will thereby assist in keeping said fluid at the required temperature to promote its evaporation. These coils, as they are drawn out of the fluid, will be wet with a thin film thereof, and the moisture of this film will be partially evaporated through the action of the heated coil and the partial vacuum in the chamber before the coil is again plunged into the fluid. The movement of these coils into, and along in and then out of the fluid produces a degree of agitation of the fluid which also promotes its evaporation.

It is, of course, to be understood that the suction fan is in constant operation, and that it will act to draw through slots 6 the produced vapor, and to produce in the evaporating chamber a partial vacuum such as will promote evaporation. As the evaporation proceeds a fresh supply of fluid may be slowly added so as to preserve the required surface level.

Having described my invention, I claim:

1. In an evaporator, the combination of an evaporating pan for containing fluid to be vaporized, a heating device, and means for repeatedly reciprocating said device to move it into and out of the fluid in the pan, during the evaporation of a given charge of fluid.
2. In an evaporator, the combination of an evaporating chamber, a heating device, means for imparting to said device a reciprocating movement which carries it repeatedly into and out of the fluid in said chamber during the evaporation of a given charge of fluid, and means for withdrawing the produced vapor from said chamber.
3. In an evaporator, the combination of an evaporating chamber, a steam carrying heating device, and means for repeatedly reciprocating said device which carries it down into and out of a fluid in said chamber, during the evaporation of a given charge of fluid.
4. In an evaporator, the combination of an evaporating chamber, an air passage by the side of the same,—the partition between said air passage and evaporating chamber having an opening through it which places said chamber and passage in communication, a suction inducing device connected with said air passage, and means for heating the contents of said chamber.
5. In an evaporator, the combination of an evaporating chamber, an air passage by

the side of the same,—the partition between said air passage and evaporating chamber having an opening through it which places said chamber and passage in communication, a suction inducing device connected with said air passage and a heating device in said chamber.

6. In an evaporator, the combination of an evaporating chamber, a steam jacket beneath the same, an air passage by the side of said chamber and in communication therewith through an opening in the partition wall between them, a suction apparatus connected with said air pocket, and a heating device in said chamber.

7. In an evaporator, the combination of an evaporating chamber, a steam heated device in said chamber, flexible tubes connected respectively with the ends of said steam device and extending out of said chamber whereby to connect the device with the source of steam and with an exhaust pipe, and means for moving said device through a path which will repeatedly carry it into and out of a fluid in said chamber, during the evaporation of a given charge of fluid.

8. In an evaporator, the combination of an evaporating chamber, a crank shaft, arms loosely hung on the cranks of said shaft, a frame loosely suspended from the lower ends of said arms, a steam heated device connected with said frame within said evaporating chamber.

9. In an evaporator, the combination of an evaporating chamber, a crank shaft, arms loosely hung on the cranks of said shaft, a frame loosely suspended from the lower ends of said arms, a steam heated device connected with said frame within said evaporating chamber, and means for producing a suction in said evaporating chamber.

10. In an evaporator, the combination of an evaporating chamber, air passages on both sides thereof separated therefrom by thin partition walls having near their upper ends openings through which the evaporating chamber is placed in communication with said air passages, a suction apparatus connected with the lower ends of said air passages, and means for heating the fluid that may be placed in said evaporating chamber.

In testimony whereof, I hereunto affix my signature in the presence of witnesses.

RICHARD J. COACH.
